Harold L. Burr

By Wilson & McLenna

Atty's.

UNITED STATES PATENT OFFICE.

HAROLD L. BURR, OF ROCKFORD, ILLINOIS.

SHIRT.

Application filed January 19, 1927. Serial No. 162,008.

This invention relates to garments generally of the sweater type, and more particularly those designed for use in athletics and popularly known as "sweat" shirts.

5 The principal object of the invention is to provide a pull-over garment of the kind referred to made of the usual heavy woven material to afford the desired warmth and having built into the sleeves thereof panels or 10 gores of ribbed knit material which, being elastic, will afford the desired amount of give so that the wearer has perfect freedom of the arms and shoulders and of the head as well and is not in the least encumbered, the 15 elasticity built into the garment being also desirable from the standpoint of making it easier to put on or take off and generally more comfortable to wear. Aside from these practical advantages secured in making the 20 garment in accordance with my invention, may be mentioned the further distinct advantage of the greatly enhanced appearance of a garment of this kind which is found to render the same much preferred to the ordinary un- 25 improved garment.

A further object of the present invention is to provide a garment made as stated above to avoid the necessity for providing as many intermediate sizes as were otherwise required 30 to be carried in stock, the minor variations in size or stature being accommodated by the elasticity of the garment.

The foregoing and other objects and advantages of my invention will appear in 35 the course of the following description, in which—

Figure 1 is a front view of a garment made in accordance with my invention, one of the sleeves thereof being shown in a position to 40 better convey an impression of the appearance of the garment; and

Fig. 2 is a plan view with the sleeves extended full length and laid flat to better illustrate the construction.

45 The same reference numerals are applied to corresponding parts in the two views.

The garment with which the present invention is concerned is commonly known as a "sweat" shirt and is used by basket ball players before and after playing or between halves, because of the great warmth thereof serving to keep the player fit. It is, however, used generally in athletics and in training quarters. The service conditions require 50 that the garment shall not encumber the wearer but should permit perfect freedom

of movement of the arms, shoulders, and the head, and, inasmuch as the garment is put on only for intervals, it also becomes important that the garment be easy to put on and take 60 off. The garment constructed as herein described meets all these requirements by reason of the great warmth of the material of which it is mainly built up and, by reason of the elasticity or give of the ribbed knit material inserted in the sleeves and shoulders and at the neck. The heavy woven material has practically no give to it but is primarily for warmth whereas the knit material affords the desired amount of give in the parts where 70 it is especially required such as in the arms and shoulders and about the neck.

In the drawing the body part of the garment designated by the reference numeral 5 is made of any suitable heavy woven material and the same is true in the main of the sleeves 6. This material is primarily for warmth and has practically no give to it and, as a result, a garment made up almost entirely of this material is hard to put on or 80 take off, is rather uncomfortable to wear, and is burdensome when the wearer is in play, inasmuch as it does not afford the desired freedom of movement of the arms, shoulders, and head. Garments of such a 85 plain, unimproved construction have been provided in the past made with a waistband 7, wristbands 8, and neckband 9 of ribbed knit material but have been considered unsatisfactory for the reasons stated. According 90 to the present invention, I provide panels or gores 10 of ribbed knit material similar to that in the waistband, wristbands, and neckband extending lengthwise of the outer sides of the sleeves 6 from the wristbands 8 up to the neckband 9, the panels being preferably in one-piece lengths, ribbed longitudinally as indicated by the lines in both views, and extending over the ridge of the shoulders, as most clearly appears in Fig. 1. 95 I prefer to have the panels 10 tapered in form narrowing from substantially the full width of the neck toward the outer ends of the arms, thus giving a proportionately greater amount of give at the shoulders 100 where it is most required and about the neck where it is also desirable from the standpoint of making the garment easy to put on and take off. Two small, V-gores 11 are provided in the shirt or body portion 5 extending down from the neck band between the shoulders at the front and back. They af- 105 110

ford the desired amount of give across the shoulders and increase the amount of give about the neck which further facilitates the matter of putting on and taking off the garment as the head can be brought through the neck band with greater ease. It is believed obvious that a garment made up in the manner described will give perfect freedom of movement for the arms, shoulders and head of the wearer and will not in any way burden the wearer if he desires to use the same during practice, for example, or in general training activity. The give afforded in the arms, across the shoulders, and about the neck easily accommodates minor variations in size or stature so that the garments made in accordance with the present invention are usually provided in sizes 30, 34, 38, and 42, instead of their having to be provided in so many intermediate sizes as, for example, 30, 32, 34, 36, etc. Aside from the practical advantages just enumerated, too much stress cannot be laid upon the fact that the present invention provides a garment of greatly enhanced appearance over anything that has been provided in the past in a similar kind of garment. The panels or gores 10 and 11 are usually provided in a contrasting color from that of the body and sleeves so as to better set off the garment and it has been found that it is much preferred to the old, plain garment because of its much improved appearance. In the cases of schools and colleges, it has been the practice to provide the present garments in the school colors with the body and sleeve materials of one color and the panels or gores together with the waist band, wrist bands, and neck band of another color.

40 It is believed that this description gives a full understanding of the present invention

so that its objects and advantages will be readily apparent to anyone skilled in the art. While in the description of the present invention special reference has been made to sweat shirts, it will be obvious that the invention is applicable to sweaters, jackets and garments of a similar general type without departing from the spirit of the invention. It is, therefore, the endeavor in the accompanying claims to include all legitimate modifications, adaptations and variations of the invention as would naturally occur to anyone skilled in the art after a disclosure of the present invention. 55

I claim:

1. A garment of the character described, comprising an overshirt of relatively non-stretchable material, the sleeves being of similar material but provided with panel inserts extending lengthwise thereof and continuing over the shoulders up to the neck, the panel material being relatively elastic to provide the desired amount of give in the proper parts of the garment. 60

2. In a garment as set forth in claim 1 wherein the neck is provided of similar material to the panels, the provision of the panels of tapered form narrowing from the neck toward the outer ends of the sleeves whereby to afford give in proportionate degrees in the arms and at the shoulders. 65

3. A garment as set forth in claim 1 wherein the panels are of tapering form narrowing from the neck toward the outer ends of the sleeves whereby to afford the desired proportionate amounts of give at the shoulders and in the arms. 70

In witness of the foregoing I affix my signature.

HAROLD L. BURR.
